UNITED STATES PATENT OFFICE.

CHARLES ROSS, JR., OF MACETOWN, NEAR DUNEDIN, NEW ZEALAND.

BLANKET-GRIP.

No. 927,286.

Specification of Letters Patent.

Patented July 6, 1909.

Application filed September 25, 1908. Serial No. 454,789.

To all whom it may concern:

Be it known that I, CHARLES ROSS, Jr., a subject of His Majesty the King of Great Britain, residing at Macetown, near the city of Dunedin, in the British Dominion of New Zealand, have invented certain new and useful Improvements in Blanket-Grips, of which the following is a specification.

This invention relates to blanket grips; and has for its object to provide a simple, cheap and efficient device for attachment to the frame of a bed or mattress for the purpose of gripping blankets or other bed covers and prevent their removal or accidentally falling off.

To this end the invention comprises a gripping device preferably operated by resilient means to grip the blanket between itself and the bed frame, a supplementary hinged grip being provided to coöperate with the main grip for producing a more secure holding device.

With these and other objects in view the invention consists of the construction, combination and arrangement of parts, herein-after described and claimed and illustrated in the accompanying drawing, in which,

Figure 1 is a front elevation of my improved grip mounted on a wooden base plate; Fig. 2, an edge view of the same with a blanket shown in position and held by the gripping device; Fig. 3, a front elevation of the base plate for the gripping device made of metal, the spring and clips which are similar to those in Fig. 1, being omitted, and; Fig. 4, represents an edge view of the same with a modified form of gripping device attached thereto.

Similar reference letters are used for the same parts in all of the figures.

In the drawing, A represents a part of a bed or mattress frame on which are fastened one or more base plates B, by means of a screw C, and held from turning by pins H, where said base plates are made of wood, as in Figs. 1 and 2, but if made of metal, as in Figs. 3 and 4, an arm integral therewith extends below and on the inside of the bed frame A to support a thumb screw C¹, which on being turned in the proper direction bears against the inside of said frame. The metal frame B is provided on its inner face with pins H which enter the outer surface of the bed frame, when the frame B¹ is tightened by the screws C¹. These pins hold said base plate from turning.

Pivotedly mounted on the base plate B is a clip E, preferably formed of wire, said clip having an elongated head parallel with the bed frame A and depending parallel arms E² joined by a cross bar E³ passing through bearings, such as staples E⁴ driven into the base plate B. Surrounding the cross-bar E³ is a coiled spring D, one end of which bears against the base plate B, while its other end extends upwardly and engages one arm E² of the clip E, tending at all times to move said clip toward the bed frame A. For convenience in retracting the frame E, a handle E¹ is hinged thereto which may be grasped by the hand and drawn outwardly against torsional action of the spring D when a blanket G is to be inserted or released from the device. The elongated head of the clip E projects above the base plate B and is bent inwardly toward the bed frame A as clearly shown in Fig. 2.

A supplemental clip F of approximately U-shape extends across the base plate B near its upper end. The sides or arms of said clip project upwardly above the top of said base plate and are hinged to the side edges of the same. In operation, after a bed has been spread the handle E¹ is grasped and the clip E drawn away from the bed, said clip rocking in the staples E⁴ and tensioning the spring D. The edge of the blanket G is drawn over the supplemental clip F and folded under the bottom bar F², thus placing the edge of said blanket between the clip F and the outer side of the base plate B. The clip E is now released and is forced by the spring D toward the bed, which action causes the blanket to be clamped between the arms E² of the clip and the supplemental clip F and between the latter and base plate B. The inwardly bent head of the clip projects over the supplemental clip and, by reason of its inclination, forces said blanket into the opening of said head, thus tightly clamping the edge of the blanket against accidental removal or falling off the bed. It is to be understood that a bed will usually be supplied with a number of these devices on each side and if desired at the foot.

A modified form of the clip is represented in Fig. 4. In this case the arms E² of said clip, are in a substantially vertical position, while the head thereof stands perpendicular to the arms and projects a short distance over the frame A of the bed. Pivotedly supported to the head E above the bed frame A

is a supplemental clip F¹, which when not in use rests against the outer corner of the bed frame A, as shown in Fig. 4. In this instance the edge of the blanket is secured in the clip by passing it between the bed frame A and the supplemental clip F¹ and then folding it around the lower end of said clip on the inner side of the arms E² of clip E. In either case any effort to remove the blanket will be resisted by the binding or gripping action of the clips, where said blanket is folded over the same.

Having thus described my invention, what I claim is:

- 15 1. A blanket grip comprising a base plate, a clip pivoted thereon and having its head bent or inclined inwardly, resilient means tending at all times to press said clip into operative position, and a supplementary clip 20 pivotally mounted on any suitable part of the grip and adapted to coöperate with the main clip for gripping the edge of the blanket.
2. A blanket grip comprising a base plate adapted to be secured on the side of a bed frame, a hinged clip mounted thereon and having a laterally elongated open head to receive a fold of the blanket, said head being bent or inclined to extend over the upper

end of said base plate and adapted to swing outwardly therefrom, and resilient means 30 tending at all times to force said hinged clip toward said base plate.

3. A blanket grip comprising a base plate adapted to be fastened to the side of a bed frame and provided with pins to prevent 35 lateral movement, a swinging clip hinged to said base plate having an elongated head bent or inclined to extend over the upper end of said base plate and provided with vertically disposed arms connected at their lower 40 ends by a cross bar, a coiled spring surrounding said cross bar and bearing at one end against said plate and at its opposite end against one of the arms of said clip, a supplemental clip pivotally connected to the sides 45 of said base plate near the top and extended across the front of the same, and a swinging handle mounted on the spring actuated clip.

In testimony whereof I have hereunto set my hand in presence of two subscribing 50 witnesses.

CHARLES ROSS, JUNR.
